Primary Examiner — Eric Goodman*Assistant Examiner* — Sloan Rozin(74) *Attorney, Agent, or Firm* — Winston & Strawn LLP(57) **CLAIM**

The ornamental design for a portable table, as shown and described.

DESCRIPTION

FIG. 1 is a perspective view of a portable table according to a first embodiment of the invention.

FIG. 2 is a perspective view of the bottom surface of the portable table of FIG. 1.

FIG. 3 is a front view of the portable table of FIG. 1.

FIG. 4 is a back view of the portable table of FIG. 1.

FIG. 5 is one end view of the portable table of FIG. 1.

FIG. 6 is an opposite end view of the portable table of FIG. 1.

FIG. 7 is a top view of the portable table of FIG. 1.

FIG. 8 is a bottom view of the portable table of FIG. 1; and, FIG. 9 is a bottom perspective view of the portable table of the invention in a collapsed configuration for transport.

1 Claim, 9 Drawing Sheets
